MACHINE FOR OPERATING UPON SOLES

Alfred S. Clark, Beverly, Mass., assignor to United
Shoe Machinery Corporation, Flemington, N. J.,
a corporation of New Jersey

Application April 28, 1949, Serial No. 90,057

32 Claims. (Cl. 12—17)

1

This invention relates to machines for operating upon soles and, more specifically, upon reinforced ribbed insoles for use in welt shoes, the machine illustrated herein being particularly adapted to cut and completely detach the opposite end portions of the rib and the reinforcing material from the heel portion of a reinforced ribbed insole forwardly to about the heel breast line of the insole.

In the manufacture of economy and similar types of channeled ribbed insoles adapted for use in welt shoes, the channeling operation for forming the sewing rib usually starts and terminates a considerable distance rearwardly of the heel breast line of the insole so that, when the channel flaps are turned upwardly and secured together to form the rib, the end portions of the rib extend rearwardly of the heel breast line at the opposite margins of the insole different distances into the heel seat portion of the insole. Moreover, when the insole is reinforced either with an all-over reinforcement of fabric material, such as canvas or Gem duck, or with fabric strips which reinforce only the rib and the adjacent body portion of the insole at the opposite margins thereof, the reinforcing material likewise extends a substantial distance rearwardly of the heel breast line of the insole into its heel seat portion. These opposite end portions of the rib and the reinforcing material which extend rearwardly of the heel breast line are of no use and, if left there, interfere with operations to be performed later on the shoe, such as the heel seat lasting operation and the weltng or inseaming operation. Heretofore, these opposite end portions of the rib rearwardly of the heel breast line have been trimmed off, if at all, by hand with the aid of a knife or other cutting tool, this practice, however, being unsatisfactory because of the damage sometimes caused to the insoles by the operator and also because of the lack of uniformity in results. Moreover, this cutting operation is difficult when performed by hand and usually takes considerable time which increases the cost of the shoe besides slowing up production. Furthermore, when this operation is performed manually with a knife, the reinforcing material covering the body portion of the insole adjacent to the opposite rib portions is not always completely severed and detached from the insole but only the fabric material reinforcing the inner sides of the rib portions is actually removed. In other words, it is difficult to detach the reinforcing material which lies flat upon the body portion of the insole adjacent to the opposite rib portions manually with a knife without damaging the insole and, consequently, this reinforcing material is not always removed, thereby leaving a rough or uneven heel seat portion on the insole. As indicated above, the operator does not always sever the opposite rib portions accurately at the heel

2

breast line of the insole and, accordingly, the insoles often vary in this respect either with regard to different insoles or the opposite margins of the same insole.

An object of the present invention is to provide an improved machine for operating upon soles constructed and arranged to cut and detach from the ribbed face of a reinforced ribbed insole the opposite end portions of the rib and the reinforcing material which extend rearwardly of the heel breast line of the insole into the heel seat portion thereof.

To the accomplishment of this object, the invention provides, in accordance with one of its features, an improved machine for operating upon soles provided with means for supporting a reinforced ribbed insole with its ribbed face exposed, a knife for making a cut heightwise of the insole through the opposite end portions of the rib and the reinforcing material at about the heel breast line of the insole, and means for severing said reinforcing material and opposite end portions from the heel portion of the insole in substantially the plane of said ribbed surface forwardly at least to the heel breast line, thereby completely detaching the rib portions and reinforcing material from the heel portion of the insole rearwardly of said heel breast line. As herein illustrated, the knife and severing means are oscillated at substantial angles to each other and in predetermined timed relation to effect the detaching operation, means being provided for actuating said members in fixed diagonal or oblique paths to cause them to cut with a slicing or shearing action, thereby to insure that they will cut completely through the materials to be detached from the insole.

The supporting means, as illustrated herein, is movable heightwise in order to position the ribbed insole relatively to the cutting means irrespective of the thickness of the insole and further means, in the form of a holdown or abutment, is provided for locating the movable support heightwise with respect to the oscillating cutting means, the abutment also serving to clamp the insole upon the support to hold it in position during the cutting operation. A gage, associated with the movable support, is provided for locating the insole longitudinally relatively to the knives, the gage, as herein illustrated, being adjustable lengthwise of the insole relatively to the support to accommodate insoles of different sizes.

In accordance with another feature of the invention, the illustrated machine is provided with means for oscillating the knife and severing means in predetermined timed relation to each other, said oscillating means being adjustable to vary the relative timing of the knife and severing means as desired. The machine also includes a one-revolution clutch for driving the oscillating means and is further provided with

single means for first moving the support heightwise to clamp the insole thereon and for thereafter tripping the clutch, said single means thus insuring that the insole will be clamped upon the support before the clutch is tripped.

The above and other features of the invention, including novel details of construction and combinations of parts will now be described in detail in connection with the accompanying drawings and thereafter pointed out in the 10 claims.

In the drawings,

Fig. 1 is a front elevation of the machine embodying the present invention;

Fig. 2 is a side elevation of the machine with 15 parts broken away or in section;

Fig. 3 is a plan view of the machine;

Fig. 4 is an enlarged front elevation of the knives of the machine operating upon an insole, the vertical knife being shown at the end of its 20 cutting movement;

Fig. 5 is a plan view of the knives with the horizontal knife located at the end of its operative movement;

Fig. 6 is an enlarged vertical section through the knives and the supporting mechanism when the knives are located in their retracted or inoperative position, an insole being shown on the support;

Fig. 7 is a vertical section through the knives 30 operating upon the insole with the knives located in the position shown in Fig. 4;

Fig. 8 is a vertical section similar to Fig. 7 when the horizontal knife has completed its operative movement as shown in Fig. 5;

Fig. 9 is an enlarged vertical section taken on the line IX—IX of Fig. 2;

Fig. 10 is a horizontal section taken on the line X—X of Fig. 9;

Fig. 11 is a perspective view of the mechanism shown in Fig. 9, the mechanism being separated and moved apart at an intermediate portion to show details more clearly;

Fig. 12 is a vertical section of the clutch mechanism taken on the line XII—XII of Fig. 2;

Fig. 13 is an enlarged sectional view taken on the line XIII—XIII of Fig. 2;

Fig. 14 is a horizontal section taken on the line XIV—XIV of Fig. 13;

Fig. 15 is an enlarged plan view showing details of the gage mechanism illustrated in Fig. 2;

Fig. 16 is a front elevation of the gage mechanism with portions of the machine shown in section;

Fig. 17 is a longitudinal section of the gage adjusting mechanism taken on the line XVII—XVII of Fig. 1;

Fig. 18 is a perspective view of the rear portion of a reinforced ribbed insole before it has been operated upon by the present machine;

Fig. 19 is a perspective view, similar to Fig. 18, after the insole has been operated upon by the machine; and

Fig. 20 is an enlarged perspective view of the right-hand margin of the insole shown in Fig. 19.

The machine of the present invention is adapted to cut and completely detach, from the heel portion of a reinforced ribbed insole, the reinforcing material and the opposite end portions of the rib which extend rearwardly of the heel breast line of the insole, thereby providing the insole with a smooth level heel seat which will improve the heel seat lasting operation on the shoe, and also terminating the opposite end por-

tions of the sewing rib at substantially the heel breast line of the insole, which will greatly facilitate and improve the welting or inseaming operation on the shoe because the operator will be able to start and finish such operation at precisely the right points at the opposite margins of the shoe bottom.

The machine is a bench type machine provided with a substantially rectangular base 24 upon which are secured by screws upstanding brackets or frame members 26, 28 (Figs. 2 and 3) which carry the operating instrumentalities of the machine. These instrumentalities comprise a vertical knife 30, a horizontal knife 32, a work support or table 34 and a holdown or abutment 36. The abutment 36 is fixed relatively to the knives and work support and the latter is elevated, as will be later explained, to move the insole against the abutment and thereby clamp the insole on the support, this movement positioning the insole heightwise relatively to the knives irrespective of the thickness of the insole.

The abutment 36, as illustrated in Figs. 1 and 2, is mounted in a vertical guideway 38 formed in a rectangular projection 40 on the bracket 26, the abutment being adjustably secured in the guideway by a screw 41 passing through a vertical slot in the abutment. The abutment 36 is adjusted heightwise in the projection 40 by a thumb screw 42 threaded into the member 40 and having a peripheral groove therein which engages a slotted arm 44 projecting inwardly from the upper end of the abutment. The heightwise position of the abutment has a direct relation to the positions of the knives 30, 32 since the abutment locates the insole relatively to the knives. The lower end of the abutment is provided with teeth 43 to cause it to grip the insole and hold it firmly on the support 34.

The vertical knife 30, as shown in Figs. 1 and 4, is adjustably secured by binding screws 46 to the front of a horizontal carrier bar 48 (Fig. 2) pivotally mounted by stud screws 50 on the lower ends of a pair of parallel arms or levers 52, 54. The arm 52 is rotatably mounted on a pin 56 secured by a set screw in a boss 58 projecting to the right, as viewed from the front of the machine, from the bracket 26. The arm 54 is secured by a taper pin 59 to the front end of a rock shaft 60 (Figs. 1, 3 and 4) rotatably mounted in a boss 62 projecting to the left, as viewed in Fig. 1, from the bracket 26, the rear portion of the rock shaft being supported in bosses 64 and 66 formed respectively on the brackets 26 and 28. This parallel or four bar linkage arrangement of the arms 52, 54 causes the vertical knife 30 to be swung downwardly obliquely in a curved or arcuate path extending transversely of the machine from the retracted position shown in Fig. 1, into the operated position illustrated in Figs. 4 and 7 to effect its cutting operation, thereby causing the knife to operate with a slicing or shearing action upon the insole, the oscillation of the knife being in a fixed predetermined path relatively to the abutment 36 and the work clamped thereby on the support 34.

The vertical knife 30 is positioned heightwise on the carrier bar 48 relatively to the arms 52, 54 by means of a pair of headed screws 68 and 70 (Fig. 4) threaded into the upper side of the bar 48 and adjustable relatively thereto, the heads of the screws serving as stops against which the upper edge of a knife may be moved

after loosening the binding screws 46. In this way the vertical knife 30 may be adjusted accurately relatively to the ribbed face of the insole upon which it acts, the screws 46 passing through slots in the knife to permit this adjustment.

In order to support the opposite end portions of the rib on the reinforced ribbed insole adjacent to the vertical knife during the cutting operation and thereby permit such portions to be slashed effectively by the knife, a rib supporting member or foot is provided in the form of an elongated horizontal bar 72 provided at its lower edge with teeth 74 which, as illustrated in Figs. 1 and 4, point toward the left as viewed from the front of the machine. The supporting foot 72 is carried by the abutment 36 by means of a forwardly extending rib on the foot located in a transverse slot 75 formed in the lower portion of the abutment, the foot being secured in the slot by a screw 76, as shown in Figs. 4 and 6. The inner surface of the supporting foot 72 is located closely adjacent to the forward face of the vertical knife 30. As illustrated in Figs. 4 and 6, when a reinforced ribbed insole A of the type referred to for use in the manufacture of welt shoes, is positioned on the support 34 and is clamped thereon by the abutment 36 through elevation of the support, the supporting foot 72 will engage the opposite end portions of the rib R and, by reason of the teeth 74 on the foot, will prevent these rib portions from bending downwardly under the action of the vertical knife 30 as the latter swings in an arc downwardly and toward the right, as viewed in Figs. 1 and 4, to perform its cutting operation. The supporting foot 72, however, does not press upon the opposite end portions of the rib, but merely rests upon them with sufficient pressure to cause the teeth 74 to engage the upper edges of the ribs and prevent them from being bent downwardly under the cutting action of the vertical knife, this support of the rib portions by the foot 72 being more effective, of course, on the left-hand rib portion, as viewed in Fig. 4, than on the right-hand portion because the left-hand portion normally slants inwardly toward the right and would thus have a natural tendency to bend inwardly and downwardly under the action of the knife, the path of which extends obliquely downwardly from left to right.

As shown in Figs. 4 to 8, inclusive, and also in Figs. 18, 19 and 20, the reinforced ribbed insole A, illustrated herein as being operated upon by the present machine, is a conventional channeled insole having a two-ply sewing rib R formed on its outer surface by the inner and outer channel flaps which are turned up and secured together in the manner usual in the manufacture of welt insoles, the inner side of the rib R and the adjacent portion of the ribbed face S of the insole, including the inside channel C, being reinforced with a strip of fabric material F, such as canvas or Gem duck, the reinforcing material covering the inside channel C and overlying a portion of the ribbed face S of the insole body upwardly of the channel. The outer margin of the reinforcing material F extends upwardly upon the inner side of the rib R and terminates substantially flush with the top of the rib.

As illustrated in Fig. 18, the end portions of the rib R at the opposite margins of the insole usually extend rearwardly a substantial distance into the heel seat portion of the insole

before the insole is operated upon by the present machine and the reinforcing material F, if the insole has been reinforced at that time, likewise extends into the heel portion at least as far as the rib portions and sometimes farther. Consequently, the heel portion of the insole, rearwardly of the heel breast line, the latter being indicated in Fig. 18 by the broken line H, contains both the opposite end portions of the rib R and the reinforcing material F which, as stated, covers the inner side of the rib R. It is these excess reinforcing and rib materials which it is desired to cut away or detach from the heel seat portion of the insole forwardly to about the heel breast line in order to obtain a smooth heel seat on the insole as well as a definite termination of the opposite end portions of the rib R at about the heel breast line, thereby permitting a better heel seat lasting operation to be performed on the shoe and also contributing to the formation of better or more uniform joints at the opposite sides of the finished shoe.

Before describing mechanism associated with the rock shaft 60 for oscillating the vertical knife 30 in the oblique or arcuate path referred to, the horizontal knife 32 will be described. As stated above, the horizontal knife 32 is adapted to sever the opposite end portions of the rib R and the reinforcing material F from the heel portion of the insole A in substantially the plane of the ribbed face S forwardly at least to the heightwise cut made by the vertical knife 30 at the heel breast line of the insole, the horizontal knife, however, preferably passing beyond the heightwise cut to insure that the opposite end portions of the rib and reinforcing material are completely severed or detached from the insole. As illustrated in Figs. 2, 3 and 5, the horizontal knife 32 is adjustably fastened by binding screws 78 and 80 to a transverse bar or carrier 82 arranged to be oscillated forwardly and rearwardly in a horizontal plane by a pair of parallel levers or arms 84, 86 pivotally connected to the carrier by pins 88 and 90, the arms entering slots (Fig. 5) formed in the rear portion of the carrier and the upper surface of the carrier engaging a hardened steel plate 92 (Fig. 2) provided on the bracket 26 to guide and support the carrier during its oscillating movement. The horizontal knife may be adjusted forwardly and rearwardly of the carrier 82 by means of counterbored slots 94 and 96 (Fig. 5) provided in the carrier and set screws 98, 100, bearing against the binding screws 78, 80 and positioning them in the slots 94, 96. The inner end of the horizontal arm 86 is pivotally connected by a pin 102 (Fig. 3) to a boss on the bracket 26 and the horizontal arm or lever 84 is similarly pivoted on a vertical pin 104 (Figs. 2 and 3) between a pair of aligned bosses 106, 108 formed on the bracket 26, the lever 84 having a rearwardly extending arm 110 which is connected by a universal joint 112 to a transverse link 114 (Fig. 9) which, in turn, is connected by a universal joint 116 to the lower arm 118 of a lever 120 (Figs. 9 and 11) rotatably mounted on the rock shaft 60. The upper end of the lever 120 is bifurcated, as shown in Fig. 11, and has a pin 122 extending between its arms and secured therein by a set screw 124. Pivot on the pin 122 is an arm 126 which extends laterally toward the right (as viewed in Figs. 9 and 11) and is rotatable on a stud 128 secured by a set screw 130 in an eccentric or crank 132, the other end of the crank being fastened by a tapered pin 134 to

a shaft 136 which forms the driving shaft of the present machine. As illustrated in Figs. 2 and 3, the driving shaft 136 is rotatably mounted in an elongated bearing 138 formed on the bracket 28. The shaft extends rearwardly and near its rearward end carries a pulley or flywheel 140 which is driven continuously from any usual source of power, such as a motor, by a belt 142, the pulley 140 being retained on the shaft by a hand wheel 144 secured to the end of the shaft by a taper pin 145. Forwardly of the pulley, the shaft 136 carries a clutch, indicated generally in Figs. 2, 3 and 12 by the numeral 146, and adapted to be tripped to rotate the shaft 136 in a clockwise direction, as viewed from the front of the machine, by a treadle rod 149 (Figs. 1 and 2) through the depression of a treadle 148 pivoted to a fixed bracket 151 in the usual manner.

The clutch 146, as best shown in Figs. 2, 3 and 12, comprises a conventional pin clutch arrangement modified somewhat in the present case to cause it to operate as a single-stroke or one-revolution clutch rather than continuously if the treadle should remain depressed, as is usual with conventional pin clutch constructions. The pulley or flywheel 140 is provided with a hollow hub portion 150 (Fig. 3) in which is mounted a plurality of forwardly extending, equally spaced projections or pins 152, usually four, through which the pulley is operatively connected to the driving shaft 136 to rotate said shaft. Rotatably mounted inside the hub 150 is a collar or sleeve 154 which, forwardly of the hub, has a shoulder 156 of larger diameter and is pinned to the shaft 136 by a pin 158, the sleeve being reduced again in diameter forwardly of the shoulder to form a hub portion 160 from which a segment 162 (Fig. 12) is removed. Mounted on the hub 160 is a semi-circular wedge piece 164 which is usual in pin clutch constructions and through the agency of which the clutch is tripped, the wedge 164 being movable axially on the shaft 136 and having a segmental projection thereon which enters the segment 162 removed from the hub 160 to keep the wedge aligned with the sleeve 154. The lefthand portion 165 of the wedge 164, as viewed in Fig. 12, tapers to a thin edge and the wedge has secured therein by a pin or set screw 167 a horizontal driving pin 166 which passes rearwardly through a hole in the sleeve 154 and has a flattened inner end for engaging any one of the four pins 152 in the hub 150 of the pulley and thereby connecting the shaft 136 to the pulley to rotate the shaft. The pin 166 is normally urged rearwardly toward the pulley by a compression spring 168 seated in a hole in the sleeve 154 which breaks into the hole through which the driving pin slides, the inner end of the spring engaging a small pin 170 projecting from the driving pin into the hole containing the spring.

The foregoing construction is substantially like that of a conventional pin clutch which will operate continuously if the treadle 149 remains depressed but will function as a single-stroke or one-revolution clutch if the treadle is released after it has been fully depressed. The wedge 164 is normally cammed forwardly to hold the driving pin 166 away from the four projections 152 by a vertical rod 172 which is mounted for heightwise movement in bearings 174, 176 (Fig. 12) provided on the bracket 28 and is urged upwardly by a spring 178 to move the upper end of the rod between the shoulder 156 on the sleeve 154 and

the wedge 164, thereby holding the driving pin 166 out of engagement with the projections 152, the spring 178 being connected at its lower end to a block 179 pinned to the rod 172 and, at its upper end, to an ear 180 secured by a screw 182 to the bearing 174 on the bracket 28. The upper position of the rod 172 is determined by the block 179 which abuts against the lower bearing 176, as shown in Fig. 12, this position locating the upper end of the rod slightly below the reduced hub portion 160 of the sleeve 154. Movement of the rod 172 downwardly from between the shoulder 156 and the wedge 164 permits the spring 168 to force the wedge and driving pin 166 rearwardly to move the pin into position to be engaged by one of the projections 152, which are rotating with the pulley 140, thereby causing the sleeve 154 and driving shaft 136 to rotate. Release of the rod 172, as for example, by release of the treadle 149, causes the spring 178 to move the rod upwardly again into the space between the shoulder 156 and wedge 164. As the wedge rotates, however, its tapered portion 165 engages the rod 172 and cams the wedge forwardly to withdraw the pin 166 from engagement with the projections 152 and thereby disconnect the clutch from the driving shaft 136. In the usual pin clutch arrangement, if the rod 172 is released immediately after the clutch is tripped, the clutch operates as a single revolution clutch but if the rod is held down, as by continued depression of the treadle, the clutch functions as a continuously operating clutch until the treadle is released.

The rod 172 is moved downwardly to trip the clutch by depression of the treadle 149 which lowers the rod 149, the latter being connected at its upper end by a pin 184 (Fig. 2) to the rearward end of a lever 186 fulcrumed at its forward end on a pin 188 fastened in lugs in the base 24. The treadle and treadle rod are normally maintained in their elevated positions by a spring 190 secured to a collar 192 fastened to the treadle rod and to a pin 194 in the base 24. At its rearward end, the lever 186 has connected thereto, by a universal joint 196, a latch 198 which, as illustrated in Fig. 12, extends upwardly beyond the shaft 136 and has formed at its upper portion a lateral projection or flange 200 which bears against the shoulder 156 of the sleeve 154. The latch 198 is provided with a projection or shoulder 202 which, when the latch is moved downwardly by the lever 186 through depression of the treadle 149 is arranged to engage a block 204 secured to the rod 172 by a set screw 206, thereby moving the rod downwardly to withdraw it from between the shoulder 156 and the wedge 164. The latch 198 is normally urged upwardly and toward the right, as viewed in Fig. 12, into engagement with the sleeve 154 by a spring 208 connected at one end to the latch and at its other end to the ear 180 previously referred to. The latch is guided in its swinging movement toward and away from the sleeve 154 by a guide member 210 secured to the bearing 174 by the screw 182 (Fig. 12) and having two horizontal arms between which the latch moves.

The shoulder portion 156 of the sleeve 154 has secured thereto by a screw 212 (Fig. 2) a wedge-shaped segment or cam 214 which, as illustrated in Fig. 12, tapers from a thin edge at one end to a relatively thick portion at its opposite end and is somewhat less than a semicircle in length. When the clutch 146 has been tripped and the shaft 136 is rotating in a clockwise direction, as

viewed in Fig. 12, the cam 214 will rotate into engagement with the lateral flange 200 on the latch 198 and move the latch outwardly, or toward the left as viewed in Fig. 12, thereby releasing the shoulder 202 from the block 204 and permitting the rod 172 to be elevated by the spring 178 to return the upper end of the rod into position between the shoulder 156 and the wedge 164. The tapered portion 165 of the wedge thereupon engages the rod 172 and cams the clutch pin 166 forwardly out of engagement with the projections 152 on the pulley 140, thereby disconnecting the driving shaft 136 from the pulley. It will be seen from the foregoing that the present construction, by withdrawing the rod 172 from the clutch indirectly through the latch 198, instead of directly by the treadle 149, permits the treadle to remain depressed without causing the clutch to repeat or to run continuously because the cam 214 will throw the latch 198 out of operation upon each revolution of the shaft 136 and thereby permit the rod 172 to raise and disconnect the clutch from operative engagement with the shaft 136. Consequently, the present clutch constitutes, in effect, a single-stroke or one-revolution clutch whether or not the treadle remains depressed. Upon release of the latch 198 during each revolution of the driving shaft 136, the spring 190 acts to return the treadle 149, the lever 186 and the latch 198 to their normal elevated positions illustrated in Figs. 2 and 12.

The latch 198 is provided with an inclined surface 216 above the shoulder 202 which, when the latch is knocked off the block 204 by the cam 214, rides upwardly past a rounded surface on the block and thus permits the shoulder 202 to pass upwardly beyond the block into a position to engage the block and trip the clutch again upon the next depression of the treadle 149. As illustrated in Fig. 12, the shoulder 202 is normally positioned a short distance above the block 204 on the rod 172 so that the treadle rod 148 must be moved downwardly a predetermined distance by depression of the treadle before the shoulder 202 will engage the block 204 and move the rod 172 downwardly away from the clutch. This lost motion allows the treadle 149 to actuate further mechanism on the machine before the clutch is tripped, thereby permitting both mechanisms to be operated in timed relation to each other by a single treadle.

The further mechanism actuated by the treadle 149 comprises mechanism for elevating the work support or table 34 to cause the insole resting thereon to be engaged by the abutment 36 and thus hold or clamp the insole on the support while being operated upon by the knives 30, 32 as well as positioning the insole heightwise relatively to the knives. The elevation of the support 34 by the treadle 149 before the clutch is tripped involves yielding mechanism which may best be explained in connection with the work support 34. Accordingly, this mechanism will be described in connection with the work support after the operation of the knives 30, 32 has been fully explained.

Referring to Figs. 9 to 11, inclusive, the crank 132 secured to the driving shaft 136 will be rotated in a clockwise direction upon actuation of the clutch 146. Accordingly, the stud 128 in the crank 132 will revolve in a clockwise direction about the axis of the shaft 136 to actuate the arm 126 and thus oscillate the lever 120 laterally upon the rock shaft 60. The lever 120,

through the link 114, will swing the horizontal lever 110 first in a counterclockwise direction, as viewed in Fig. 3, and then in the opposite direction, thereby actuating the parallel arms 84, 86 and oscillating the horizontal knife 32 in substantially the plane of the work and in a predetermined oblique or arcuate path relatively to the insole on the support 34. As stated above, the horizontal knife 32 is backed up during its oscillating movement by the plate 92 which engages the upper side of the carrier 82. Preferably, the knife 32 is inclined on a slight angle, for example, 2° to the horizontal, to facilitate its cutting action.

15 The parallel arms 52, 54 (Figs. 1 and 4), which actuate the vertical knife 30, are operated by oscillation of the rock shaft 60 through a lever 218 (Figs. 10 and 11) secured to the rock shaft by a taper pin 220. The upper end of the lever 218 carries a shoulder screw 222 fastened therein by a nut 224 and having pivotally mounted thereon a laterally extending arm 226 which, at its opposite end, is rotatably mounted on a shaft 228 secured by a set screw 230 in an eccentric or crank 232, the opposite end of the crank having a short shaft 234 formed thereon which projects forwardly in alignment with the driving shaft 136 and is rotatably mounted in a bearing 236 (Figs. 2 and 3) formed on the bracket 26.

20 It will be seen from the foregoing, that the bifurcated lever 120, which actuates the horizontal knife 32, is rotatable upon the rock shaft 60 and oscillates freely thereon, whereas the lever 218, which actuates the vertical knife 30, is pinned to the rock shaft and consequently oscillates this shaft to actuate the vertical knife through the parallel arms 52 and 54, the latter of which is pinned to the rock shaft by the pin 59.

25 The knife actuating mechanism is adjusted 30 in the following manner. The stud 128 (Fig. 11), which is secured in the rear crank 132 by the set screw 130, extends through the lateral arm 126 and has a reduced forward portion 238 which is rotatable in a block 240 arranged for movement between parallel arms formed on a bifurcated member 242 secured upon the inner end of the shaft 228 between the lateral arms 126 and 226 by a set screw 243. The bifurcated member 242 has a screw 244 threaded through the outer ends of its parallel arms which may be tightened to clamp the block 240 in different positions between these arms. This adjustment of the block 240 in the bifurcated member 242 changes the angular positions of rotation of the eccentrics or cranks 132, 232 relatively to each other and consequently changes the relative angular positions of the axes 128, 228, carried respectively by the cranks 132, 232 and upon which the lateral arms 126 and 226 are rotatably mounted. It also 35 changes the positions of these two axes with respect to the driving shaft 136 and the aligned shaft 234, about which the cranks themselves rotate. This adjustment, therefore, controls or varies the timing of the strokes or throws of the lateral arms 126, 226 relatively to each other and thus controls the timing of the relative operation of the knives 30 and 32. After an adjustment has been made in this mechanism to obtain the desired relative operation of the knives 30 and 32, the screws 243 and 244 are tightened 40 and the mechanism is ready to operate. Rotation of the driving shaft 136 by the clutch in a clockwise direction as viewed from the front of the machine, rotates the crank 132 about the axis of the shaft 136 and, through the arm 126,

45

50

55

60

65

70

75

oscillates the lever 120 on the rock shaft 60, thereby operating the horizontal knife through the mechanism previously described. The bifurcated member 242, through the reduced end 232 of the stud 128 rotatable in the block 240, is caused to revolve with the crank 132 around the shaft 136 and thereby cause the shaft 228 to revolve about this same axis but in a different timed relation to the revolution of the stud 128 about said axis, revolution of the shaft 228 about the axis, of course, operating the other lateral arm 226, this crank shaft mechanism being completed by the forward crank 232, in which the shaft 228 is fastened, and the short shaft 234 on this crank which rotates in the forward bearing 230. The revolution of the arm 226 around the axis of the shaft 136 in a different timed relation to the revolution of the rearward arm 126 about such axis, causes the lever 218, which is pinned to the rock shaft 60, to oscillate said rock shaft and actuate the forward arm 54 thereon, thereby causing the parallel arms 54, 52 to swing in the proper direction and timed relation with respect to the horizontal knife 32 to cause the vertical knife 30 to be oscillated heightwise in an oblique arcuate path extending downwardly from left to right to perform its cutting operation, the cutting action, as stated above, being a slicing or shearing action to facilitate cutting through the opposite end portions of the rib R and the reinforcing material F substantially down to the exposed ribbed face S of the insole or deeper if desired.

The foregoing arrangement it will be noted constitutes, in effect, a double crank construction with adjusting means embodied therein for varying at will the relative eccentricity or throw of the cranks with respect to each other without disassembling the mechanism and thereby control the operation of the knives 30 and 32 with respect to the timing of their cutting movements relatively to each other. After a desired adjustment of the block 240 in the bifurcated member 242 has been made and the binding screws 243, 244 in the member 242 have been tightened, the mechanism operates as a solid crank about the axis of the driving shaft 136. As stated, the lateral arm 126 oscillates the lever 120 upon the rock shaft 60 whereas the arm 226 oscillates the rock shaft 60 itself which actuates the forward parallel arms 54, 52 and thus oscillates the vertical knife 30.

Figs. 4 to 8, inclusive, illustrate the relative positions of the knives 30 and 32 during one complete cycle of the machine with the knives set in accordance with one adjustment of the crank mechanism described above. As shown in Fig. 6 the knives 30, 32 are initially located in their inoperative or retracted positions and the heel portion of the insole A has been positioned on the support or table 34, as will be later explained, with its ribbed face S exposed and ready to be operated upon. The support 34 has been elevated, in a manner to be hereinafter described, to move the insole into engagement with the stationary abutment 35 and thus clamp the insole upon the support, the teeth 43 on the abutment and the knurling 246 on the support 34 preventing the insole from slipping during the cutting operation. The operator trips the clutch 146 by depressing the treadle 149 thereby causing the machine to operate through one cycle only. The vertical knife 30 descends obliquely from the position shown in Fig. 6 to that shown in Figs. 4 and 7, thereby cutting heightwise through the op-

posite end portions of the rib R and the reinforcing material F at approximately the heel breast line of the insole, the position of the insole on the support 34 determining the exact position of this cut lengthwise of the insole, as will be later explained.

The vertical knife actually travels in a transverse arc from left to right as it moves downwardly and thus has a slicing or shearing effect upon the insole as it cuts transversely through the opposite rib portions and reinforcing material at about the heel breast line of the insole. The supporting mechanism can be adjusted so the cut made by the vertical knife will terminate substantially at the ribbed face S of the insole or, if desired, will extend slightly below or into said face. This insures that the materials to be severed from the heel seat portion of the insole will be cut completely through by the vertical knife. As illustrated in Figs. 4 and 7 the vertical knife 30 has cut diagonally through the opposite end portions of the rib R and the reinforcing material F downwardly to a plane slightly below the ribbed face S of the insole, thereby insuring that the fibers of the materials, particularly the leather fibers of the opposite rib portions, have been cut completely through down to the ribbed face S. The heightwise cut can, however, be made to terminate substantially at, or in the plane of, the ribbed face S if desired, for example, if the insole is composed of material less fibrous than leather, such as artificial leather, plastic, fabric, paper or the like.

It will be noted in Fig. 7 that, when the vertical knife 30 has completed its downward stroke, the horizontal knife 32 has simultaneously moved forwardly relatively to the heel end of the insole in substantially the plane of the ribbed face S so that it is located in a position just behind the vertical knife when the latter completes its downward movement. The timing of the cutting operations in the present machine is preferably so close that the vertical knife 30 just starts to withdraw from the insole at the time that the horizontal knife 32 meets and passes the heightwise cut, the action, of course, being very rapid. This close timing of the relative cutting actions of the knives can be obtained in the present machine by the fine adjustments permitted in the crank mechanism by the adjusting mechanism described above. It should be also mentioned that the cutting edges of the knives 30 and 32, although quite wide, are parallel to each other at all times during the cutting operation.

The horizontal knife 32, as illustrated in Figs. 5 and 8, is preferably adjusted on its carrier 82 so that it passes somewhat beyond the heightwise cut made by the vertical knife 30 and thus insures that the opposite end portions of the rib R and the reinforcing material F rearwardly of the heel breast line of the insole will be completely detached or separated therefrom, thereby eliminating the possibility of leaving portions of the ribs or reinforcing material partially attached to the insole so that it would be necessary to complete the separation of the materials by hand with a knife or scissors after the insole had been operated upon by the machine. The fact that the cutting edge of the vertical knife is just leaving its cut in the insole as the parallel cutting edge of the horizontal knife passes through or intersects this cut, not only accelerates the operation of the machine but produces an excellent cutting operation because the materials are partially supported by the knives as well as by the usual sup-

porting elements of the machine when the relative actions of the knives are timed as close as they are in the present machine. The oscillation of the knives 30, 32 by the actuating mechanism is quite rapid so that the oblique slicing action of the knives will be as effective as possible or, in other words, so that it will imitate the motion of cutting the materials by hand with a knife. Figs. 7 and 8 illustrate the detachment of the opposite end portions of the rib R and the reinforcing material F from the heel seat portion of the insole A forwardly to about the heel breast line H by the two knives 30 and 32 and Figs. 19 and 20 show how the insole will appear after these materials have been detached and removed from the heel portion of the insole.

The support or table 34 is moved upwardly to bring the insole into engagement with the stationary abutment 36 in the following manner. As illustrated in Figs. 1 and 2, the support 34 is carried on the upper end of a rectangular post 248 which is mounted for heightwise movement in a housing 250 projecting forwardly from the base 24, the bottom of the housing being closed by a plate 252 and its front wall having a rectangular opening 254 (Fig. 1) formed at its lower end. The lower end of the post 248, as shown in Fig. 2, is inclined upwardly from front to rear at an angle of about 15° to the horizontal and rests upon the upper face of a correspondingly inclined wedge 256, the post being normally held downwardly against the wedge by a spring 258 extending between the upper end of the support and a hook 260 fastened to the housing by a screw 262. Movement of the wedge 256 forwardly or toward the left, as viewed in Fig. 2, will elevate the support 34 to move the insole resting thereon against the abutment 36 and thereby clamp the insole on the support. Movement of the wedge in an opposite direction permits the spring 258 to lower the support at it rides downwardly on the inclined face of the wedge.

The wedge 256 is moved forwardly to elevate the support 34 by the treadle rod 148 through depression of the treadle 149. Pivotally connected to the wedge by a pin 264 is an adjustable rod or link 266 which is pivotally connected at its other end by a pin 268 to a downwardly extending lever 270 fulcrumed on a horizontal shaft 272 secured in a pair of lugs 214, 276 (Figs. 2, 13 and 14) projecting downwardly from the upper wall of the base 24. The lever 270, as illustrated in Fig. 13, is fulcrumed on the shaft 272 next to the lug 276. At the other side of the lever 270 is mounted a bushing or collar 278 having a circular flange 280 on one end equal in diameter to the hub of the lever 270 and provided with a plurality of radially spaced holes 282. A lever 284 is fulcrumed on the shaft 272 between the collar 278 and the lug 276, this lever, as shown in Fig. 2, being connected by a pin 286 to a short link 288 which, in turn, is connected by a pin 290 to the treadle-actuated lever 148. Surrounding the collar 278 between the flange 280 and the lever 284 is a torsion spring 292, one end of which is looped around a pin 294 fixed in the flange 280, and the other end of which engages a pin 296 fastened in the lever 284, thereby tending normally to swing the lever 284 counterclockwise, as viewed in Fig. 2, about the shaft 272 and to rotate the collar 278 in the opposite direction. The collar is prevented from turning on the shaft 272 relatively to the lever 270 by a locking pin 297 inserted through a hole in the lever into one of the spaced holes 282 in the flange 280. The ten-

sion of the spring 292 may be adjusted by removing the locking pin 297, turning the collar 278 on the shaft 272 to tighten or loosen the spring and then reinserting the pin through the lever 270 and into whichever hole in the flange 280 registers with that in the lever.

The forward portion of the lever 284, as shown in Fig. 14, is bent at right angles to form a laterally extending lug 298 which is arranged to engage a projection or lip 300 formed on the upper portion of the lever 270. Normally the spring 292 maintains the lug 298 against the projection 300, as shown in Fig. 2, to cause the mechanism to be rotated as a unit by depression of the treadle 149. However, when the lever 270 is prevented from swinging further in a counterclockwise direction by engagement of the insole on the support 34 with the abutment 36, the spring 292 yields to permit the lever 284 to continue its counterclockwise movement with the lever 148 until the treadle is fully depressed. Depression of the treadle, therefore, lowers the treadle rod 148 and, through the mechanism just described, swings the lever 270 clockwise, as viewed in Fig. 2, to slide the wedge 256 forwardly or toward the left and thus elevate the support 34 until the insole thereon engages the stationary abutment 36, thereby clamping the insole on the support and positioning the insole heightwise relatively to the knives 30, 32. The wedge 256 will be maintained in its forward position by the increased tension of the spring 292 as the treadle is further depressed acting in conjunction with the relatively small inclination of the wedge. The treadle 149 can thereafter descend further, through the yield in the spring 292, until the treadle is depressed sufficiently to trip the clutch 146 through the pivoted latch 198, as previously explained. A stop screw 302 (Fig. 2) is provided on a lug on the wedge 256 for engaging the front wall of the base 24 to limit forward movement of the wedge if no insole should be mounted on the support 34, thereby preventing elevation of the support far enough to damage the knives if the clutch should happen to be tripped when no work was in the machine. As illustrated in Figs. 1, 2 and 3, fixed aprons 303 are provided at opposite sides of the support 34 to facilitate the introduction of the insoles onto the support, the aprons slanting downwardly away from the support, as shown in Figs. 1 and 2.

The insole A is positioned longitudinally on the support 34 by a back gage 304 which projects upwardly beyond the inner end of the support 34 and is in position to engage the heel end of the insole when the latter is placed on the support heel end first by the operator. The gage 304, as illustrated in Figs. 2, 15 and 16, comprises a substantially vertical plate which is adjustable forwardly and rearwardly of the machine to accommodate insoles of different sizes. The gage is provided with a downwardly extending lug 306 having a horizontal keyway therein whereby the gage can be initially positioned longitudinally on a key 308 provided on a slide 310, the gage being secured to the slide by a screw 311 passing through a slot in the lug 306. The slide 310 is slidable on the base 24 beneath a fixed cover plate 312 extending laterally of the gage and provided with a keyway or slot 314 which extends lengthwise of the plate and receives a key on the slide 310, thereby guiding the slide forwardly and rearwardly of the support 34. The cover plate 312 is secured to the base by screws 316 and is cut 75 away on its lower side to provide clearance for a

laterally extending arm 318 on the slide 310, the arm carrying a pin 326 which projects downwardly through a slot 321 (Fig. 17) in the base 24 and has an enlarged head 322 which is arranged to engage and ride in the thread of a screw 324 (Figs. 2 and 17) secured to a shaft 326 by a pin 323. The shaft 326 is rotatable in the base 24 in a forward bearing formed by the base and a rear bearing 330 which projects downwardly from the upper wall of the base. The shaft is provided at its forward end with a hand wheel 332 secured thereto by a set screw 334, the hand wheel having a dial 336 with graduated markings thereon to indicate the position of the gage 304 relatively to the support for insoles of different sizes. The shaft 326 also carries a knurled thumb nut 338 secured to the front end of the shaft by a set screw 340 (Fig. 17) and by means of which the initial position of the dial 336 relatively to the shaft 326 and screw 324 for different types of insoles may be determined. The shaft 326 has a reduced inner portion 342 upon which is mounted a compression spring 344, the spring being seated in a cup nut 346 threaded on the shaft and held in position by a check nut 348. The spring 344 bears against a washer between it and the rear bearing 330 and urges the shaft 326 rearwardly to maintain the screw 324 firmly against the rear bearing, thereby eliminating any looseness or play in the adjusting mechanism.

Rotation of the hand wheel 332 will move the gage 304 forwardly or rearwardly to position the gage longitudinally of the support 34 in accordance with the size of insole being operated upon, the force of the spring 344 maintaining the gage in adjusted position until moved by the operator. The support 34, shown diagrammatically in Fig. 15, is provided with a rectangular opening 352 into which the gage 304 may be moved when adjusted forwardly to accommodate the smaller sizes of insoles. Since the knives 30 and 32 are wider than the largest insole to be operated upon, no means is necessary for positioning the insole widthwise of the support, the insole being centralized manually on the support by the operator so that the abutment 36 will always engage the insole between the opposite rib portions R.

In setting the back gage 304 for operating upon different insoles, the gage is first adjusted along the key 383 for the particular type of insole being operated upon because the position of the heel breast line will vary somewhat in different types of insoles, for example, insoles for men's, women's and children's shoes or an insole which is to receive one kind of heel compared to another insole of the same size which is to take a different kind of heel. The hand wheel 332 is next set relatively to the shaft 326 for the particular type of insole being operated upon, this being done by loosening the hand wheel and turning the shaft relatively thereto by the thumb nut 338. The back gage 304 is then adjusted forwardly or rearwardly by the screw 324 until the dial 336 indicates that the gage is in the proper position for the particular size of insole being operated upon.

The knives of the present machine operate in predetermined fixed paths with quick positive strokes and it is essential, therefore, that some means be provided for guarding the knives when the machine is operating in order to protect the operator from injury. The rear portion of the machine, including the pulley 140 and the mechanisms located forwardly thereof are preferably covered by sheet metal hoods which are secured to the base 24 in the usual manner by screws.

Figs. 1 and 2 show a portion of a hood 354 which covers the operating mechanisms located in front of the pulley 140. The mechanism extending forwardly of the hood 354, including the knives 30 and 32, as illustrated in Fig. 2, are covered in the present machine by a transparent plastic cover or guard 356 which is substantially rectangular in shape and is hinged to the forward side of the hood 354 by a wide hinge 353, the upper wall of the guard 356 having an opening therein to permit the head of the thumb screw 42 to project upwardly therethrough. The guard 356 is normally positioned as illustrated in Figs. 1 and 2 so that it covers the knives 30, 32 and the operating mechanism adjacent thereto in order to guard this mechanism and prevent injury to the operator, the front wall of the guard being cut back, as shown at 360 in Fig. 1, to provide space for the introduction of the insole onto the support 34. When it is necessary to grind the knives or to make adjustments in the operating mechanisms of the machine, the guard 356 may be swung upwardly on its hinge 353 and be retained in an upwardly extending position by a leaf spring or latch 362 secured to the hood 354, thereby permitting the operator to make the adjustments.

In order to insure that the operator will not be able to trip the clutch and start the machine when the guard 356 is held in its upper position by the latch 362, the following mechanism is provided. A stationary foot 364 (Figs. 1 and 2) is secured to the upper wall of the guard 356 and projects downwardly inside the guard, as shown in the figures referred to. The lower end of the foot is arranged to engage a downwardly and forwardly inclined surface formed on the front end of a lever 366 secured to a horizontal rod 368 rotatably mounted in bearings provided on the brackets 26 and 28. Secured to the rearward end of the rod 368 by a set screw 370 is a downwardly extending lever or dog 372, the lower end of which is provided with a projection or shoulder 373 as illustrated in Fig. 12. The projection 373 is arranged to swing under the block 204 on the vertical rod 172, which is retracted by the treadle to trip the clutch 140 so that, when the projection is located under the block 204, the rod 172 cannot be moved downwardly away from the clutch. The dog 372 is urged inwardly into engagement with the block 204 by a spring 374 (Figs. 2 and 3) secured at one end to an arm 376 fastened by a set screw to the rod 368, the spring being secured at its opposite end to a pin 378 mounted in a lateral projection 380 on the bracket 28. The spring tends normally to rotate the rod 368 in a clockwise direction as viewed in Fig. 1. Accordingly, when the guard 356 has been swung downwardly into its operative position, the foot 364, through its engagement with the lever 366, holds the dog 372 away from the block 204 and thus permits the rod 172 to be withdrawn from the clutch by the treadle rod 148 upon depression of the treadle 149. However, if the guard 354 has been latched upwardly by the leaf spring 362, or even if the guard has been moved upwardly a short distance by the operator out of its lower operative position, the spring 374 moves the dog 372 under the block 204 and thereby prevents downward movement of the rod 172 and tripping of the clutch until the guard 354 has been swung downwardly again into its operative position.

As stated above, the knives 30 and 32 may be adjusted on their carriers to adapt them for particular types of insoles or to compensate for

variations in the knives due to grinding. The paths of movement of the knives are fixed, however, the vertical knife 30 oscillating in a predetermined vertical plane and the horizontal knife 32 oscillating in a predetermined horizontal plane. In order to set the machine, therefore, for operating upon all insoles irrespective of their thicknesses, the abutment 36 is adjusted heightwise relatively to the horizontal knife 32, this adjustment depending, of course, upon the thickness of the layer of material, if any, which is to be cut or skived from the heel portion of the insole. This adjustment may be readily made by placing an insole upon the support 34, elevating the support until the exposed surface of the heel seat portion of the insole engages the bottom surface of the horizontal knife 32, and then lowering the abutment 36 until it engages the exposed face of the insole. If it is desired to cut a thin layer or skiving from the surface of the insole, in addition to the opposite rib portions and reinforcing material, this may be done by elevating the abutment the required amount by the adjusting screw 42 after the thickness of the insole has been measured by the procedure previously explained. The position of the abutment 36, therefore, determines the thickness of the cut made by the horizontal knife 32 and, since the stroke of the vertical knife 30 is gaged with reference to the position of the horizontal knife, the position of the abutment 36 determines the depth to which the vertical knife will cut. After the elements of the machine have been adjusted insoles of all thicknesses may be operated upon successively without any further adjustment because each insole will be located in the proper heightwise position relatively to the knives by the abutment 36. Accordingly, the adjustments need not be changed until a skiving of a different thickness is to be removed from the heel portion of the insole. The back gage 304, of course, determines the position of the heightwise cut made by the vertical knife 30 lengthwise of the insole, this cut, as stated, being located approximately at the heel breast line of the insole. Accordingly, one setting of the gage 304 may be used for all insoles of a particular size. Although the operation of the machine will be apparent from the foregoing description, a brief summary of its operation will be given here for the purpose of clearness.

The operator places the heel portion of the reinforced ribbed insole A with its ribbed face S facing upwardly on the forwardly extended portion of the support 34 and he slides the insole rearwardly until its heel end engages the gage 304. He then depresses the treadle 149 which moves the wedge 256 forwardly to elevate the support 34 and move the insole into engagement with the stationary abutment 36, as illustrated in Fig. 4, the opposite portions of the sewing rib R adjacent to the heel breast line being engaged by the foot 72 to maintain the ribs in their up-standing position. Further depression of the treadle lowers the treadle rod 148 further, which is permitted by yielding of the torsion spring 292, to cause the latch 198 to engage the block 294 on the vertical rod 172 and withdraw the rod from the clutch 146, thereby tripping the clutch to rotate the driving shaft 136, the machine operating through only one complete revolution of the driving shaft 136. Rotation of the shaft 136 causes the vertical knife 30 to be swung downwardly in its predetermined oblique path to cut heightwise

through the opposite end portions of the rib R and the reinforcing material F at about the heel breast line H of the insole, the mechanism preferably being set as previously described, to make 5 a cut which terminates substantially at the ribbed face S of the insole, thereby cutting through the reinforcing material which covers said face and also covers the inner sides of the rib portions. Preferably the heightwise cut will terminate a 10 short distance below the ribbed face S of the insole, as illustrated in Figs. 4 and 7, to insure cutting completely through the fibers of the material, particularly if the insole is composed of leather or similar fibrous materials.

15 Simultaneously with the operation of the vertical knife 30, the horizontal knife 32 is moved forwardly by its actuating mechanism, the cutting action of the horizontal knife starting an inch or so rearwardly of the heel breast line of 20 the insole so that it will always be located rearwardly of the opposite end portions of the rib which extend rearwardly of the heel breast line of the insole into the heel seat portion thereof. The horizontal knife moves forwardly in a pre- 25 determined oblique path extending from left to right, as viewed from the front of the machine, and in substantially the plane of the ribbed face S of the insole to sever the opposite end portions of the rib and the reinforcing material F from 30 the heel portion of said face forwardly at least to the heightwise cut made by the vertical knife. As 35 stated above and as illustrated in Figs. 4 to 8, inclusive, the horizontal knife 32 preferably reaches the heightwise cut at the heel breast line of the insole just after the vertical knife has moved out of the plane of the horizontal knife so that the two knives will pass each other quite closely without striking in the normal operation 40 of the machine, this timing of the knives, however, being variable by the adjustment provided in the actuating mechanism by the bifurcated member 242, the block 249 and the clamping screw 244. The horizontal knife intersects the heightwise cut made by the vertical knife, as 45 illustrated in Fig. 8, and passes a short distance beyond said cut to insure that the severed materials will be completely detached or separated from the ribbed face of the insole. Immediately following the completion of the operation of the knives, they are swung back again into their open 50 or retracted positions by their operating mechanisms which, as explained above, operate through only one cycle by reason of the one-revolution clutch 146.

55 During the first part of the operating movement of the knives, that is, after the first quarter of the rotation of the driving shaft 136, the wedge-shaped cam 214 (Fig. 12), associated with the clutch 146, engages the latch 198 and releases 60 it from the block 204, thereby permitting the rod 172 to be elevated by the spring 173 in ample time to prevent the possibility of the clutch repeating. The rod 172 is thus in position to engage the segmental wedge 164 and cam the latter forwardly to withdrawn the pin 166 from the projections 152, thereby throwing out the clutch after one revolution of the shaft 136 and stopping the operation of the machine.

65 After the cutting operation has been completed, the operator releases the treadle 149 which allows the spring 190 to elevate the treadle and treadle rod 148 and withdraw the wedge 256, thereby permitting the spring 258 to lower the support 34 so that the operator can remove the insole and position a new insole upon the support.

Release of the treadle also permits the latch 198 to ride upwardly past the block 204 on the rod 172 and thus be in a position to engage the block and lower the rod away from the clutch upon the next depression of the treadle. Since the operation of the machine is quite rapid, the operator is not actually obliged to hold the treadle depressed, but merely to depress the treadle at an ordinary or normal speed until it is depressed to the floor and then to release it, the operation of the knives being completed in the time it takes to depress the treadle its full distance.

It should be pointed out that the present machine is adapted to operate upon ribbed insoles before they have been reinforced with fabric material as well as after the reinforcing material has been applied thereto. In other words, a ribbed insole which has not had any reinforcing material applied to the inner side of the rib R or the inner channel C could be operated upon by the present machine, if desired, to cut and detach the opposite end portions of the rib R which extend rearwardly of the heel breast line of the insole, thereby preparing the insole for receiving the reinforcing material which might then be applied to the rib and the adjacent body portion of the insole from the heel breast line at one side of the insole to the heel breast line at the opposite side thereof, these points having now been definitely established on the insole by the present machine. When operating upon an unreinforced insole, the horizontal knife could, through adjustment of the abutment 36, be positioned to cut substantially in the plane of the ribbed face S of the insole or, if desired, to cut in a plane located parallel to, but a short distance below, such face in order to remove a thin layer or skinning from the heel seat portion of the insole and thereby provide a smooth level surface at said heel seat portion.

It should also be pointed out that the present machine is adapted to operate upon insoles having preformed ribbed strips or tape ribs attached thereto by cement or stitches, many of these insoles having attached tape ribs thereon which extend indeterminate distances rearwardly of the heel breast line into the heel seat portion of the insole. The machine can be adjusted to cut off and detach only the upstanding rib portions of the preformed ribbed strip or to cut off the rib portion and also the flange or base portion of the strip. If the preformed tape rib has been attached to the insole by stitches instead of cement, as is the case with some insoles in use today, the present machine will sever the stitches as well as the tape rib strip and thus detach the opposite end portions of the rib completely from the heel portion of the insole without damaging the ribbed face of the insole.

Having thus described my invention, what I claim as new and desire to secure by Letters Patent of the United States is:

1. A machine for operating upon soles having, in combination, means for supporting a reinforced ribbed insole with its ribbed face in position to be operated upon, a knife for making a cut heightwise of the insole through the reinforcing material and opposite end portions of the rib approximately at the heel breast line of the insole, said cut terminating substantially at said ribbed face, means for severing the reinforcing material and opposite end portions of the rib from the heel portion of said ribbed face forwardly to the heightwise cut, thereby detaching said reinforcing material and opposite end por-

tions from the insole, means for actuating said knife, and separate means for actuating said severing means, said two last-named means being constructed and arranged to move said knife and said severing means in predetermined oblique paths which cause them to operate with a slicing action upon said reinforcing material and opposite end portions of the rib.

2. A machine for operating upon unattached soles having, in combination, rigid means for supporting a reinforced ribbed insole with its ribbed face exposed, a knife movable both heightwise and widthwise of the insole for making a transverse cut through the reinforcing material and opposite end portions of the sewing rib at about the heel breast line of the insole, said knife cutting approximately flush with said ribbed face, and cutting means movable in substantially the plane of said ribbed face for severing therefrom the reinforcing material and opposite end portions of the rib which extend rearwardly of said transverse cut, thereby detaching the reinforcing material and opposite end portions of the rib from the insole rearwardly of its heel breast line.

3. A machine for operating upon soles having, in combination, a non-yieldable support for positioning and holding the rear portion of a reinforced ribbed insole in position to be operated upon with its ribbed face exposed, an oscillating knife arranged to move heightwise and widthwise of the insole to make a cut through the opposite end portions of the rib and the material reinforcing said rib and adjacent body portion of the insole at approximately the heel breast line thereof, said cut extending transversely of the insole at least to said ribbed face, and an oscillating knife operable in substantially the plane of said ribbed face for severing the reinforcing material and opposite end portions of the rib from the heel portion of the insole forwardly to the transverse cut, said last-named knife passing beyond said transverse cut to insure the complete detachment of the reinforcing material and opposite end portions of the rib from the insole body rearwardly of its heel breast line.

4. A machine for operating upon soles having, in combination, a support for a ribbed insole, a knife movable heightwise and widthwise of the insole for making a cut transversely thereof through the opposite end portions of the rib at approximately the heel breast line of the insole, a knife movable lengthwise and widthwise of the insole in substantially the plane of the ribbed face of the insole for severing the opposite end portions of the rib from the heel portion of said ribbed face forwardly at least to the transverse cut, thereby completely detaching said end portions from the insole rearwardly of its heel breast line, a driving shaft, and means for actuating said knives from said driving shaft.

5. A machine for operating upon unattached soles having, in combination, a flat support for positioning and supporting an unattached reinforced ribbed insole in a flat position with its ribbed face exposed, means separate from the support for holding the insole thereon, an oscillating knife for making a transverse cut heightwise of the insole through the reinforcing material and opposite end portions of the rib at substantially the heel breast line of the insole, said cut extending at least to said ribbed face, an oscillating knife for severing the reinforcing material and opposite end portions of the rib from the heel portion of the insole in substantially the plane of said ribbed face forwardly at

least to said transverse cut, thereby completely severing said material and opposite end portions of the rib from the insole rearwardly of its heel breast line, and power-operated means for oscillating said knives in predetermined timed relation to each other.

6. A machine for operating upon soles having, in combination, a rigid support for holding a reinforced ribbed insole with its ribbed face exposed, an abutment for clamping the insole on said support, a reciprocating knife for making a transverse cut heightwise of the insole through the reinforcing material and opposite end portions of the sewing rib at about the heel breast line of the insole, said cut terminating approximately at said ribbed face, a knife reciprocable in a plane substantially parallel to said ribbed face for cutting from the insole the reinforcing material and opposite end portions of the rib which extend rearwardly of said transverse cut, said last-named knife passing beyond said transverse cut and thereby completely detaching said reinforcing material and opposite rib portions from the insole rearwardly of said heel breast line, and means for operating said knives constructed and arranged to move said last-named knife past the first-named knife immediately after completion of the transverse cut by said first-named knife.

7. A machine for operating upon soles having, in combination, a support for positioning and supporting a reinforced ribbed insole with its ribbed surface exposed, an oscillating knife for making a transverse cut heightwise of the insole through the reinforcing material and the opposite end portions of the rib at about the heel breast line of the insole, said cut terminating approximately at said ribbed surface, a second knife arranged to oscillate in a plane substantially parallel to said ribbed surface for severing the reinforcing material and opposite end portions of the rib from the heel portion of said surface forwardly to said transverse cut, said second knife passing beyond said transverse cut to insure the complete detachment of the severed materials from said heel portion, means for supporting the opposite end portions of the rib, and power-operated means for oscillating said knives constructed and arranged to cause the first knife to complete its operative stroke and commence to withdraw immediately prior to the movement of the second knife past said transverse cut.

8. A machine for operating upon soles having, in combination, a pair of knives arranged for operative movement in planes located substantially at right angles to each other, a pair of pivoted arms for operating each knife and for maintaining the cutting edges of said knives constantly in parallel relation to each other during their operative movement, and means for oscillating said pairs of arms so that the respective paths of the knives intersect each other, said means being constructed and arranged to oscillate each pair of arms in such timed relation to the other pair that the knives avoid contact with each other.

9. A machine for operating upon unattached soles having, in combination, a support for locating and holding a reinforced ribbed insole with its ribbed face in position to be operated upon, an oscillating knife for making a transverse cut heightwise of the insole through the reinforcing material and opposite end portions of the rib at approximately the heel breast line

of the insole, said knife terminating its cut substantially flush with said ribbed face, an oscillating knife operable in a plane substantially parallel to said ribbed face for severing the reinforcing material and opposite end portions of the rib from the heel portion of the insole forwardly to said transverse cut, said last-named knife continuing its operative movement beyond the transverse cut thereby completely separating the materials from the insole, and separate means for actuating each knife constructed and arranged to cause each knife to travel in a predetermined oblique path extending widthwise of the insole during its oscillating movement and thereby have a shearing effect upon said materials.

10. A machine for operating upon soles having, in combination, a support for holding a reinforced ribbed insole with its ribbed surface exposed, means for clamping the insole on said support, means for moving the support relatively to said clamping means, a reciprocating knife for making a cut heightwise of the insole through the reinforcing material and the opposite end portions of the rib at substantially the heel breast line of the insole, said knife cutting at least to said ribbed surface, a knife reciprocable in a plane substantially parallel to said ribbed surface for severing said reinforcing material and opposite end portions of the rib from the heel portion of the insole forwardly beyond said heightwise cut, thereby intersecting said heightwise cut and detaching the reinforcing and rib materials completely from the insole, and power-operated means for simultaneously reciprocating said knives in predetermined curved paths and in timed relation to each other to cause each knife to exert a slicing action upon the insole, said means being constructed and arranged to cause said knives to pass extremely close to each other without striking during their operating movement.

11. A machine for operating upon soles having, in combination, a support for holding a ribbed insole with its ribbed face exposed, a knife for making a cut heightwise of the insole through the opposite end portions of the rib at about the heel breast line of the insole, said cut terminating adjacent to said ribbed face, a second knife for severing the opposite end portions of the rib from the heel seat portion of the insole forwardly at least to the first-named cut to detach the severed materials completely from the insole, means for actuating the first knife, means for actuating the second knife, connections between said actuating means for causing the knives to operate in predetermined timed relation to each other, and means for adjusting said connections to vary said timed relation.

12. A machine for operating upon soles having, in combination, a support for positioning and holding a reinforced ribbed insole with its ribbed face in position to be operated upon, a knife for making a cut heightwise of the insole through the reinforcing material and the opposite end portions of the rib at about the heel breast line of the insole, said cut extending transversely of the insole and terminating approximately at said ribbed face, a second knife operable in a plane substantially parallel to said ribbed face for severing the reinforcing material and opposite end portions of the rib from the heel portion of the insole in substantially the plane of said ribbed face, said second knife having its cutting edge constantly parallel to the cut-

ting edge of the first knife and being arranged to travel forwardly beyond the transverse cut of said first knife to ensure the complete detachment of the materials from the insole, a crank for actuating the first knife, a crank for actuating the second knife, connections between said cranks for causing them to actuate the knives in predetermined timed relation to each other without striking, and means for adjusting said connections to vary said timed relation.

13. A machine for operating upon soles having, in combination, means for cutting and detaching the opposite end portions of a sewing rib from the heel portion of a ribbed insole forwardly to approximately its heel breast line, means for supporting said insole with its ribbed face in position to be operated upon by said cutting means, an abutment for clamping the insole on said supporting means, means carried by the abutment for supporting the opposite end portions of the rib, and means for effecting relative movement between the supporting means and abutment to clamp the insole on said supporting means.

14. A machine for operating upon unattached soles having, in combination, oscillating means for cutting and completely detaching the reinforcing material and opposite end portions of a sewing rib from the heel portion of a reinforced ribbed insole forwardly to about its heel breast line, means for supporting said insole with its ribbed face exposed and in position to be operated upon by said oscillating means, an abutment for clamping the insole on said supporting means, and manually-operated means for moving the supporting means relatively to the abutment to cause the latter to clamp the insole on said supporting means.

15. A machine for operating upon soles having, in combination, means for cutting and detaching the opposite end portions of a sewing rib from an insole rearwardly of its heel breast line, means for supporting said insole with its ribbed face in position to be operated upon by said cutting means, an abutment for clamping the insole on the supporting means, said abutment being normally spaced from said supporting means, means on said abutment for supporting the opposite end portions of the rib during the cutting operation, and treadle-operated means for moving the supporting means toward the abutment to clamp each insole thereon with its ribbed face in the same plane relatively to the cutting means irrespective of its thickness, said treadle-operated means acting also to maintain the supporting means in sole-clamping position during the cutting operation.

16. A machine for operating upon soles having, in combination, oscillating means for severing and completely detaching the opposite end portions of a rib from the heel portion of a ribbed insole forwardly to about the heel breast line of said insole, a movable support for holding the insole in position to be operated upon by said oscillating means, a stationary abutment for clamping the insole on said support, means normally holding the support away from said abutment, a wedge engaging said support, and means for moving the wedge relatively to the support to move the latter toward the abutment and cause said abutment to clamp the insole on the support, said last-named means serving also to retain the support in sole-clamping position during the severing operation.

17. A machine for operating upon soles hav-

ing, in combination, a plurality of knives arranged to oscillate in predetermined paths located at substantial angles to each other for severing and completely detaching from the heel portion of a reinforced ribbed insole the reinforcing material and opposite end portions of the rib forwardly to about the heel breast line of the insole, a support for positioning and holding the insole with its ribbed face in position to be operated upon by said knives, an abutment located in a predetermined position relatively to said knives, and means for effecting relative movement between the support and said abutment to clamp the insole on said support, said means positioning the ribbed face of the insole relatively to said knives so that the latter will detach the reinforcing material and opposite end portions of the rib from the ribbed face of the insole without damaging said ribbed face irrespective of the thickness of the insole.

18. A machine for operating upon soles having, in combination, a pair of knives reciprocable in oblique paths located substantially at right angles to each other for shearing and completely severing from the heel seat portion of a reinforced ribbed insole the reinforcing material and opposite end portions of the rib forwardly to about the heel breast line of the insole, a power-operated means for reciprocating said knives in said paths, a movable support for positioning and supporting the insole in position for its ribbed face to be operated upon by said knives, a stationary abutment initially spaced from said support and located in a predetermined position relatively to the paths of said knives, and treadle-operated means for moving the support toward said abutment to clamp the insole on said support, said abutment and support locating the ribbed face of the insole in a position in which the knives will shear the reinforcing material and opposite end portions of the rib from the heel seat portion of said ribbed face forwardly to about the heel breast line of the insole irrespective of the thickness of said insole, said treadle-operated means serving also to hold the support in sole-clamping position during the severing operation.

19. A machine for operating upon unattached soles having, in combination, a pair of knives arranged to oscillate in predetermined paths located substantially at right angles to each other for cutting and detaching from the ribbed face of a reinforced ribbed insole the reinforcing material and opposite end portions of the rib at the heel portion of the insole forwardly to about its heel breast line, said knives having their cutting edges parallel at all times and terminating their cutting movements on substantially the same line in the insole, power-operated means for oscillating said knives, a support for holding the ribbed face of the insole in position to be operated upon by said knives, a stationary abutment spaced from said support and located in a predetermined position relatively to the line on which the knives terminate their cutting movement, and manually-operated means for moving the support toward said abutment to clamp the insole on said support, said abutment locating the ribbed face of the insole in a position relatively to said knives in which the latter will cut and detach said reinforcing material and opposite end portions of the rib from the ribbed face of the insole without damaging the body portion of the insole irrespective of the thickness of said body portion.

20. A machine for operating upon soles having, in combination, a knife for making a cut heightwise of a ribbed insole through the opposite end portions of the rib at approximately the heel breast line of the insole, said cut terminating substantially at the ribbed face of the insole, cutting means operable in a plane substantially parallel to the plane of said ribbed face for severing said opposite end portions of the rib from the heel portion of said ribbed face forwardly to the heightwise cut, said means being arranged to pass beyond said heightwise cut to detach said end portions completely from the insole, means having a generally flat roughened surface thereon for positioning said insole in a single plane with its ribbed face exposed in a position to be operated upon by said knife and cutting means, and means cooperating with the positioning means for holding the insole in such position.

21. A machine for operating upon soles having, in combination, a knife for making a cut heightwise of a ribbed insole through the opposite end portions of the rib at the rear portion of the ribbed face of the insole, said cut terminating substantially at said ribbed face, cutting means operable substantially in the plane of said ribbed face for severing the opposite end portions of the rib from the heel portion of the insole forwardly to the heightwise cut, said cutting means being arranged to pass beyond said heightwise cut to detach said end portions of the rib completely from the insole, a support for holding the insole while it is being operated upon by said knife and cutting means, means for positioning said support relatively to the knife and cutting means, and means separate from the support for locating the insole on said support in a position in which said knife will make said heightwise cut substantially at the heel breast line of the insole.

22. A machine for operating upon soles having, in combination, a knife having a straight cutting edge for making a cut heightwise of a ribbed insole through the opposite end portions of the rib at about the heel breast line of the insole, said cut terminating substantially at the ribbed face of the insole, cutting means operable substantially in the plane of said ribbed face for severing the opposite end portions of the rib from the heel portion of said ribbed face forwardly to the heightwise cut, said means being arranged to pass beyond said heightwise cut to detach said opposite rib portions completely from the insole, a flat support for holding the ribbed face of the insole in a single flat plane while it is being operated upon by said knife and cutting means, a gage separate from the support for locating the insole on said support in a position in which the knife will make said heightwise cut substantially at the heel breast line of the insole, and means independent of the support for adjusting said gage toward and away from said support in a plane parallel to the plane of said ribbed face.

23. A machine for operating upon unattached soles having, in combination, a knife for making a cut heightwise of a ribbed insole through the opposite end portions of the rib at about the heel breast line of the insole, said cut terminating adjacent to the ribbed face of the insole, cutting means operable substantially in the plane of said ribbed face for severing the opposite end portions of the rib from the heel portion of the insole forwardly to said heightwise

cut, said means being arranged to pass beyond the heightwise cut to detach the opposite rib portions completely from the insole, a support for the insole, a gage adjacent to the support for locating the heel portion of the insole in a position in which the knife will make its heightwise cut substantially at the heel breast line of the insole, manually-operated means for adjusting said gage relatively to the support to accommodate insoles of different lengths, and means for maintaining said gage in adjusted position.

24. A machine for operating upon soles having, in combination, means for cutting and detaching the opposite end portions of a sewing rib from the heel portion of a ribbed insole forwardly to about its heel breast line, power-operated means for actuating said means, a support for holding the insole in a position to be operated upon by the cutting means, said support being initially spaced below said cutting means but being movable heightwise into operative position relatively thereto, a clutch for driving said power-operated means, and means for moving the support heightwise into said operative position and for tripping said clutch.

25. A machine for operating upon soles having, in combination, a pair of knives for cutting and completely detaching the opposite end portions of a sewing rib from the heel portion of a ribbed insole forwardly to about its heel breast line, power-operated means including cranks for actuating said knives in predetermined paths in timed relation to each other, a movable support spaced from said knives for supporting the insole with its ribbed face in position to be operated upon, a one-revolution clutch for driving said power-operated means, and single means for moving said support into operative position relatively to said knives and for thereafter tripping said clutch, said single means acting also to hold the support in said operative position during the operation of said knives.

26. A machine for operating upon soles having, in combination, a pair of oscillating knives movable at substantial angles to each other for cutting and completely detaching from the heel portion of a reinforced ribbed insole the opposite end portions of the rib and the fabric material reinforcing said heel portion and said rib forwardly to about the heel breast line of the insole, said knives oscillating in predetermined oblique paths which intersect each other in a plane adjacent to the ribbed face of the insole, thereby completely slicing said reinforcing material and opposite rib portions from said ribbed face, power-operated means for oscillating said knives in predetermined timed relation to each other, a support movable relatively to said knives for holding the insole with its heel portion in position to be operated upon, a stationary abutment spaced from said support for clamping the insole thereon, a single-revolution clutch for driving said power-operated means, and treadle-operated means for first moving the support toward said abutment to clamp the insole on the support and for thereafter tripping said clutch, said treadle-operated means including a wedge constructed and arranged to move the support toward said abutment and then to maintain said support in operative position during the oscillation of said knives.

27. A machine for operating upon soles having, in combination, a knife for making a cut in a plane extending heightwise of a sole, a second knife for making a cut in a plane substan-

tially parallel to the plane of the sole, a driving shaft, a crank rotatable with said shaft, a lever pivotally connected to said crank for actuating the second knife, a second crank rotatable about the same axis as the first crank, a lever pivotally connected to the second crank for actuating the first knife in timed relation to the second knife, and means for changing the relative positions of angular rotation of said cranks about their axes and thereby varying the operation of said knives relatively to each other.

28. A machine for operating upon soles having, in combination, a knife for making a cut in a plane extending heightwise of a sole, a second knife for making a cut in a plane lying substantially parallel to the plane of the sole, a driving shaft, a crank rotatable with said shaft, a lever pivotally connected to said crank for actuating the second knife, a second crank rotatable about the same axis as the first crank, a lever pivotally connected to the second crank for actuating the first knife in predetermined timed relation to the second knife, and means interconnecting said cranks for changing the relative positions of said levers and thereby varying the timed relation of the operation of said knives relatively to each other.

29. A machine for operating upon soles having, in combination, a knife for making a cut in a sole at an angle to the plane thereof, a second knife for making a cut in the sole at a substantial angle to the first cut, a driving shaft, a crank rotatable with said driving shaft, a lever rotatable about a stud carried by said crank, connections between said lever and the second knife for actuating said second knife, a second crank rotatable about the same axis as the driving shaft, a shaft carried by the second crank, a second lever rotatable about the shaft carried by said second crank, connections between said second lever and the first knife for actuating said knife in timed relation to the second knife, a bifurcated arm rotatably mounted on the last-named shaft, a block movable on said arm and having one end of said stud rotatable therein, and means for securing said block in different positions on said arm to change the angular positions of said cranks relatively to each other, thereby varying the timed relation of the operation of said knives.

30. A machine for operating upon soles having, in combination, a knife for making a cut heightwise of a sole, a second knife for making a cut substantially parallel to the plane of the sole, said knives being arranged to make cuts which intersect each other in a single plane in the sole, a driving shaft, a crank secured to said shaft, a lever rotatable about a stud fixed in said crank, connections between said lever and the second knife for actuating said second knife in a plane substantially parallel to the plane of the sole, a second crank rotatable about the same axis as the driving shaft, a second lever rotatable about a shaft carried by said second crank, connections between said lever and the first knife for actuating said first knife heightwise of the sole and in timed relation to the second knife, a bifurcated member rotatably mounted on the last-named shaft, a block slidably in said member and having a free end of said stud rotatable therein, and means for locking said block in different positions in said bifurcated member, thereby changing the

angular relation of the cranks relatively to each other and varying the timed relation of the operation of said knives.

31. A machine for operating upon soles having, in combination, a knife for making a transverse cut heightwise of a reinforced ribbed insole through the reinforcing material and the opposite end portions of the rib substantially at the heel breast line of the insole, said knife terminating its operative stroke approximately flush with the ribbed face of the insole, a second knife for making a cut in a plane substantially parallel to the plane of said ribbed face at the heel portion of the insole and forwardly toward the transverse cut, said knife traveling beyond said transverse cut to sever the reinforcing material and opposite end portions of the rib completely from the heel portion of the insole rearwardly of said transverse cut, a driving shaft, a crank rotatable with said driving shaft, a lever pivotally connected to said crank, connections including a parallel link arrangement between said lever and the second knife for oscillating said knife in an oblique path in a plane substantially parallel to the plane of said ribbed surface, a second crank rotatable about the same axis as the driving shaft, a second lever pivotally connected to said second crank, connections including a parallel link arrangement between said second lever and the first knife for oscillating said knife in an oblique path heightwise of the insole and in timed relation to the oscillation of the second knife, a bifurcated arm mounted on the pivot of said second lever, a block movable along said arm and having the pivot of said first lever rotatable therein, and means for locking said block in different positions along the bifurcated arm, thereby varying the timed relation of the oscillation of said knives relatively to each other.

32. A machine for operating upon soles having, in combination, a knife mounted on a pair of parallel arms for making a transverse cut heightwise of a ribbed insole through the opposite end portions of the rib at approximately the heel breast line of the insole, said cut terminating substantially at the ribbed face of the insole, a second knife mounted on a pair of parallel arms movable at an angle to said first knife for severing the opposite end portions of the rib from the heel portion of the insole in substantially the plane of said ribbed face, means for moving the second knife beyond the transverse cut of the first knife to detach said end portions completely from the insole, and means for operating said pairs of arms in timed relation to cause the knives to do their work.
